PAGE 2

Fig. 2

Fig. 3

Fig. 4

Figure 1 is a front elevational view of a lubricator, filter and regulator unit, showing my new design;

Figure 2 is a side elevational view thereof;

Figure 3 is a top plan view; and

Figure 4 is a side elevational view opposite to Figure 2.

I claim:

The ornamental design for a lubricator, filter and regulator unit, as shown.
